ELIHU D. WATT, OF LA GRANGE, ILLINOIS, ASSIGNOR TO RAYMOND CONCRETE PILE COMPANY, OF NEW YORK, N. Y., A CORPORATION OF NEW JERSEY.

APPARATUS FOR ERECTING COMPOSITE PILES.

1,135,086.

Specification of Letters Patent. Patented Apr. 13, 1915.

Application filed May 10, 1912. Serial No. 396,289.

To all whom it may concern:

Be it known that I, ELIHU D. WATT, a citizen of the United States, residing at La Grange, county of Cook, and State of Illinois, have invented certain new and useful Improvements in Apparatus for Erecting Composite Piles, of which the following is a full, clear, and exact description.

In many locations it is desirable to drive a wooden pile or shaft beneath the earth-surface or water level, and to superimpose upon and unite with it a reinforced concrete column in such manner that wood and concrete are formed into a unitary pile-structure. For example, in forming stable foundations for structures, such as docks or buildings, in marshy land, or in piling work extending out into tide-waters, lakes or the like, conditions are met with in which composite wood and concrete piles are highly desirable.

My invention is designed to build up such composite piles, and to make them substantial, permanent and unitary.

In the accompanying drawings, Figure 1 represents a longitudinal section of my apparatus, attached to the head of a wooden pile. Fig. 2 is a similar view showing a partly-completed pile. Fig. 3 is a section on line 3-3 of Fig. 1; and Fig. 4 is a section on the line 4-4 of Fig. 2.

A represents a wooden shaft or pile; B a cylinder, which may be made of metal or wood, and of sufficient diameter to fit over the head of the pile.

C is a block, serving, if desired, both as anvil and templet, as will be hereinafter described, designed to fit loosely inside the cylinder B and to rest upon the head of the pile A. D is a second cylinder, which may be concentric with the outer cylinder B, and operatively connected with the block C, as by the bolt E.

F is a plate set upon, and uniting the upper or outer ends of the two cylinders B and D, and G is a striking block or anvil set upon the plate F. The plate F may be removably attached to the outer cylinder B, as by hooks H, engaging with eyes I on the block F and wires or cords J attached to similar eyes I' in the cylinder B.

K K are lag-screws or other substantial metallic rods which project through holes O in the block or plate C and penetrate the head of the wooden pile a sufficient depth

to develop the strength of their rods as a means of permanently uniting the concrete and the wooden parts of the structure when completed.

L L are longitudinal metallic reinforcements for the concrete, which may be cross-braced and united with the lag-screws K by metallic reinforcements M.

N is a shell, preferably of thin sheet metal, of slightly less diameter than the external pipe B, which may be employed as a permanent inclosure for the concrete, if desired.

S is a metal band that may be applied to the head of the wooden pile to prevent the wood from splitting during or after the driving of the lag-screws K K.

The manner of using my apparatus is this: Before the wooden pile A has been raised by the pile driver, holes of the proper size are bored in the head of the wood pile from a templet made according to the spacing of holes O in the plate C, and either before the wooden pile A has been raised by the pile driver, or after it has been driven in the usual manner until its upper end is almost down to the level of the earth or water, the lag screws K are screwed into the pile head, so that they project upward between the inner and outer cylinders D and B and through the holes O in plate C and project firmly and to a considerable length into the wooden pile head A; and the device or follower is attached as shown in Fig. 1. That is to say, the block O with its attached and coöperating parts is mounted on the upper end of the pile A, with the outer cylinder B projecting a considerable distance over the head of the pile, to assist in holding it straight during the process of driving.

Then, the pile and follower being in complete alinement and in proper position for driving, a pile driver or other suitable machine is employed to hammer upon the anvil G, and thus force both wooden pile A and the follower to any desired depth in the earth or beneath the surface of the water. Thereupon, the upper plate F, carrying with it, and connected to, all parts of the follower except outer cylinder B, is withdrawn either after complete disconnection from outer cylinder B or by a sufficiently long connection J to permit of all parts of the follower except B being raised above the top of part B. This leaves the wooden pile A in place with

its head at some distance below the ground or water, with outer cylinder B projecting over it and extending above the ground or water, with the rods or lag screws K projecting into outer cylinder B above, and firmly in place in the wood pile below. Next, I place in proper place within said cylinder B the additional metal reinforcements L and M, which may be accomplished by sliding them down the lag-screws or rods K; and if desired, the metal cylinder N, which is only slightly smaller than cylinder B, so as to slide down into cylinder B without appreciable friction, or allow cylinder B to be withdrawn without enough friction to disturb cylinder N in its position. (Cylinder N may be of very thin material, since the pressure of the ground or water is taken by cylinder B). Thereafter cylinder N is filled with concrete, using such force as may be necessary to compact it above and about the wooden pile head, which latter may be beveled off as at P, to make a more extensive contacting surface, also compacting the concrete about the reinforcement L and M and the lag screws K. During this concrete filling operation, or at any other time, the outer cylinder B may be withdrawn as by means of the hooks H and cords or cables J or the eyes I, according to the conditions of earth or water, as will be fully understood by those skilled in the art.

It will be observed that the lag screws K serve both as a means to maintain the alignment of the follower with the wood pile during the final driving of pile A and the construction of the concrete structure upon it, and to firmly and permanently unite the concrete structure R with the wood, also that outer cylinder B furnishes an efficient means of guiding the head of the wood pile, so as to avoid any tendency on the part of the wood pile to lean to one side or the other, thus tending to make the complete composite structure straight and free from turns or bends at the joint.

When the concrete has fully set, the structure will be complete, and it will embody a rigid, unitary, but composite structure, the wooden part meeting local conditions that make its use preferable at the lower end, and the upper part of concrete to comply with conditions that make its use advantageous there.

As will be readily understood, my invention is susceptible of great mechanical variation in form, material and arrangement of parts; it is useful in all situations where a composite structure of the character indicated is desirable; not merely where earth or water conditions necessitate a wooden lower part and a concrete upper part, but, for example, where a greater length of pile is required than can be practically supplied by a wooden shaft alone, or by a reinforced

concrete pile alone, whether pre-molded or formed-in-place. My invention will be found especially useful when, through threatened or actual sinking of structures already built, it is necessary to drive pre-existing wooden piles to a greater depth and build up their upper ends to support the existing structure. 70

Manifestly, my device, or follower, may be of any length desired or found necessary in practice, and may be made in longitudinal sections without departing from my invention. 75

What I claim as my invention is:

1. In an apparatus for erecting piles, the combination of a cylinder, a head for each end thereof, the lower head being provided with perforations, lag-screws projecting through said perforations and adapted for permanent engagement with a pile-head, an outer cylinder and means for withdrawing said lower head through said outer cylinder upon the lifting of the upper head, substantially as and for the purposes described. 80

2. In an apparatus for erecting piles, a follower comprising means for detachable engagement with a wooden pile-head, an anvil for receiving force from a pile driver, means for transmitting such force to the wooden-pile head, lag-screws permanently attached to said pile head, a perforated block within said follower through which said lag-screws project, and means for permitting withdrawing of said follower from said wooden pile-head, substantially as and 100 for the purposes described. 95

3. In an apparatus for erecting piles composed of a wooden shaft, surmounted by a concrete shaft, the combination of a series of lag screws driven into said wooden shaft 105 and upstanding from the same, a driving member mounted upon said lag screws comprising a lower head to slide upon said lag screws and to be in contact with the head of the wooden shaft, an outer cylinder, an inner cylinder permanently attached to said lower head, an upper head attached in fixed relation to said inner cylinder and detachably secured to said outer cylinder, substantially as and for the purpose set forth. 110 115

4. In an apparatus for erecting composite piles composed of a wooden shaft and a series of metallic reinforcing rods permanently affixed to and projecting upwardly from the upper end of the wooden shaft, 120 comprising means slidably mounted upon said metallic rods and operatively connected to said wooden shaft and a member supported by the wooden shaft adapted to receive cementitious material for forming a 125 concrete shaft upon said wooden shaft, substantially as and for the purposes set forth. 130

5. In an apparatus for erecting composite piles composed of a wooden shaft and a series of metallic reinforcing rods perma-

nently affixed to and projecting upwardly from the upper end of the wooden shaft, comprising means slidably mounted upon said metallic rods and operatively connected to said wooden shaft, means adapted to transmit driving force to said wooden pile, and a member supported by the wooden shaft adapted to receive cementitious material for forming a concrete shaft upon said wooden shaft, substantially as and for the purposes set forth.

6. In an apparatus for erecting composite piles composed of a wooden shaft and metallic structure permanently affixed to and projecting upwardly from the upper end of the wooden shaft, comprising a pile driving

member slidably mounted upon said metallic structure and adapted to transmit driving force to said wooden pile and a cylindrical member connected to the upper end of the wooden shaft adapted to inclose the cementitious material forming a concrete shaft upon said wooden shaft in which the said metallic structure is embedded, substantially as and for the purposes set forth.

In testimony whereof I affix my signature in the presence of two subscribing witnesses.
